ALARM SET AND STOP MECHANISM

Raymond V. Adduci, Waterbury, Conn., assignor
to The United States Time Corporation, Water-
bury, Conn., a corporation of Connecticut

Application September 20, 1946, Serial No. 698,264

3 Claims. (Cl. 58—21.15)

1

This invention is concerned with timepieces having an alarm consisting of an audible or visible means. The particular embodiment chosen for illustrating the invention consists of an alarm clock having the usual bell-type alarm. The invention set forth in this application is similar in many respects to that described and claimed in co-pending application No. 681,334 by Henry S. Braze and Thomas R. Claffey and constitutes an improvement thereover.

In an alarm clock, it is necessary to provide some means for setting the alarm to be sounded at the desired time, and it is also the usual practice to provide some means for stopping the alarm after it has started to operate or for preventing its operation entirely. It has been the customary practice in the past to provide a knob on the back of the clock which may be turned to set the alarm to be sounded at any predetermined time and to provide another knob or button on the back, or sometimes on the top, of the clock which may be pulled "out" to place the alarm in readiness to function when the predetermined time arrives or which may be pushed "in" to prevent the alarm from functioning.

It is an object of this invention to provide a single control means on the back of an alarm clock or other timepiece for performing both the function of setting the alarm and conditioning or stopping the alarm, which means will be simple and positive in operation.

Further objects and advantages of the invention will appear as the disclosure proceeds.

Referring now to the drawing wherein:

Fig. 1 is a side elevational view, partly in section, of the alarm control mechanism of this invention.

Fig. 2 is a view of another embodiment of a portion of the alarm control mechanism.

Fig. 3 is a still further embodiment of the alarm control mechanism of this invention.

Referring now to Fig. 1, a portion of the usual frame plates of the clock are indicated at 2 and 4. A staff 6 is shown rotatably mounted between said frame plates and the staff 6 carries an alarm escape wheel 8 and an escape wheel pinion 10. The escape wheel 8 and the pinion 10 are rigidly connected to the staff 6 by staking or in any other desired manner. Also rotatably mounted between the frame plates 2 and 4 is shown a staff 12 having rigidly connected thereto, or formed integrally therewith, the usual alarm hammer having a verge 14. The pallets of the verge are indicated at 16 and 18 and these pallets are engaged by the teeth of the alarm escape wheel 8

so that upon rotation of the escape wheel, the verge 14 carrying the alarm hammer will be rocked back and forth to cause the alarm to be sounded in the usual well-known manner. As will readily be appreciated, the escape wheel pinion 10 is driven by the usual alarm train. The alarm train together with the verge and hammer comprise the alarm sounding mechanism.

A knob 20 is shown rigidly connected with a staff 22, and the staff 22 is mounted between the frame plates 2 and 4 in such manner that it is capable of movement according to two types of motion; namely, rotary and longitudinal. Rigidly connected to the end of the staff 22 opposite from the knob 20 is the usual alarm set wheel pinion 24 which meshes with the alarm set wheel partially shown at 26.

A resilient means in the form of a preferably flat spring-like member is indicated at 28 and the member 28 is rigidly connected to the rear frame plate 4 by means of a rivet 30, or in any other desired manner. The member 28 is provided intermediate its length with a curved offset portion 32 for a purpose to be presently described, and the free end 34 of the resilient member 28 is constructed and arranged to be moved into engagement with the pallet 18 of the verge 14 as will presently be described.

The staff 22 is provided with an enlarged crowned portion 36 which may be formed integrally with the staff or which may be rigidly secured thereto in any desired manner. The crown of the portion 36 is the point of greatest diameter and is indicated at 38. The enlarged portion of the staff tapers off from the crown abruptly on one side as shown at 40 and gradually on the other side as shown at 42.

With the staff 22 in the full line position shown in Fig. 1, the intermediate portion 32 of the resilient member 28 engages the abrupt taper 40 and releasably holds the staff 22 in this position. It is to be noted that at the time the intermediate portion 32 of the member 28 is engaged with the abrupt taper 40, the end 34 is out of engagement with the pallet 18 of the verge 14 so that the hammer may be oscillated by the escape wheel 8. When the control knob 20 is pushed "in," that is to the left as seen in Fig. 1, the intermediate portion 32 of the resilient member 28 rides up over the crown 38 and becomes engaged with the gradual taper 42 of the enlarged portion 36. Even this gradual taper 42 is sufficient to cause the staff 22 to be releasably held in the dotted line position shown in Fig. 1, but since the tapered portion 42 is of larger mean diameter than the

portion 40, the intermediate portion 32 of the member 28 is raised to the dotted line position seen in Fig. 1 and the end 34 is likewise raised to the dotted line position and engages the pallet 18 of the verge 14 of the alarm hammer to thereby prevent the hammer from oscillation and the alarm from sounding. Inasmuch as pallet 18 is integral with verge 14, it is to be interpreted that end 34 engages the verge 14.

Since it is usually desirable that the alarm set wheel 26 be turned in only one direction, a means has been provided for preventing the staff 22 from rotating in more than one direction, and this means is shown in the form of a one-way brake, generally indicated at 44. The one-way brake 44 consists of a spring wire member wound as shown at 46 around a cylindrical hub 48 of the enlarged portion 36. The wire 46 is provided with a tail portion 50 having a loop 52 in its outer end and the loop 52 loosely surrounds a stud 54 fixed in the rear frame plate 4. The wire 46 is wound around the hub 48 in such manner as to allow the hub 48 and the staff 22 to be freely rotated in one direction, but so that upon attempted rotation of the staff 22 in the opposite direction, the wire 46 will tightly coil about the hub 48 to prevent the same from rotating. The loose fit of the loop 52 over the stud 54 allows the entire brake mechanism 44 to move longitudinally with the staff 22.

The width of the pinion 24, which serves to set the alarm, is such that it will engage the alarm set wheel 26 when staff 22 is in either of its two longitudinal positions. Therefore, the alarm may be set either when the knob 20 is in its "in," or alarm stopping position, or when the knob is "out," or in alarm sounding position. Also the alarm set wheel can never be turned in more than one direction since it is turned only by the pinion 24, fast with the staff 22, which as pointed out above can be turned in only one direction due to the one-way brake 44. The brake 44 moves longitudinally with the staff 22 due to the loose fit of the loop 52 over the stud 54.

The embodiment of the invention shown in Fig. 2 differs only slightly from that shown in Fig. 1, and the identical parts have been given the same reference numerals as used in Fig. 1 for convenience and ease of illustration. In the form of the invention shown in Fig. 2, the gradual taper 42 of the enlarged portion 36 is replaced by a cylindrical portion 42' which is curved abruptly as shown at 56 up to the crown 38. While the resilient member 28 is shown in dotted line as well as full line position, it is to be understood that the member 28 moves longitudinally only in relation to the staff 22 and that actually the member 28 is fixed to the rear frame plate as shown in Fig. 1 while the staff moves longitudinally between two positions in the same manner as illustrated in Fig. 1. The abrupt portion 56 leading from the crown 38 down to the cylindrical portion 42' serves the purpose of more securely holding the staff 22 in its "in" position.

The embodiment of the invention shown in Fig. 3 differs from that shown in Fig. 2 only in the provision of a flange 58 having substantially the same diameter as the crown portion 38. When the intermediate portion 32 of the resilient member 28 is engaged within the groove between the crown 38 and flange 58, the staff 22 is more securely, though releasably, held in the "in" or alarm stopping position than in either of the other embodiments.

While the invention has been illustrated and

described in its preferred embodiments and has included certain details, it should be understood that the invention is not to be limited to the precise details herein illustrated and described since the same may be carried out in other ways, falling within the scope of the invention as claimed.

What I claim is:

1. A timepiece having a pair of frame plates which support components of an alarm train and alarm setting means and said train including an escape wheel and an alarm hammer having a verge engaging said escape wheel; in combination with a manually operable staff supported by said frame plates for longitudinal movement between two positions and also for rotatable movement, a pinion on said staff engageable with said alarm setting means and operable upon rotation of said staff to vary the position of said setting means, a round crowned member fixed to said staff, the mean diameters of the surfaces of said member on opposite sides of the crown thereof being different, and a resilient member supported adjacent one end by one of said frame plates and having an intermediate portion slidably engageable with said crowned member and normally disposable on one or the other of said surfaces on opposite sides of said crown thereof to maintain the staff in one of said two positions thereof, the other end of said resilient member being shaped to engage said verge when the intermediate portion of said member engages the surface on one side of the crown of said crowned member but not engage said verge when said intermediate portion engages the surface on the other side of said crown.

2. A timepiece having a pair of frame plates which support components of an alarm train and alarm setting means and said train including an escape wheel and an alarm hammer having a verge engaging said escape wheel; in combination with a manually operable staff supported by said frame plates for longitudinal movement between two positions and also for rotatable movement, a pinion on said staff engageable with said alarm setting means and operable upon rotation of said staff to vary the position of said setting means, a round crowned member fixed to said staff and having a cylindrical portion, the mean diameters of the surfaces of said member on opposite sides of the crown thereof being different, a resilient member supported adjacent one end by one of said frame plates and having an intermediate portion slidably engageable with said crowned member and normally disposable on one or the other of said surfaces on opposite sides of said crown thereof to maintain the staff in one of said two positions thereof, the other end of said resilient member being shaped to engage said verge when the intermediate portion of said member engages the surface on one side of the crown of said crowned member but not engage said verge when said intermediate portion engages the surface on the other side of said crown, and a one-way clutch spring surrounding the cylindrical portion of said crowned member and arranged to grip said portion to prevent rotation of the staff in one direction but not when rotated in the other direction.

3. A timepiece having a pair of frame plates which support components of an alarm train and alarm setting means and said train including an escape wheel and an alarm hammer having a verge engaging said escape wheel; in combination with a manually operable staff supported by said frame plates for longitudinal movement be-

tween two positions and also for rotatable movement, a pinion on said staff engageable with said alarm setting means and operable upon rotation of said staff to vary the position of said setting means, a round crowned member fixed to said staff and having a cylindrical portion, the mean diameters of the surfaces of said member on opposite sides of the crown thereof being different, a resilient member supported adjacent one end by one of said frame plates and having an intermediate portion slidably engageable with said crowned member and normally disposable on one or the other of said surfaces on opposite sides of said crown thereof to maintain the staff in one of said two positions thereof, the other end of said resilient member being shaped to engage said verge when the intermediate portion of said member engages the surface on one side of the crown of said crowned member but not engage said verge when said intermediate portion engages the surface on the other side of said crown, an elongated pin fixed relative to one of said frame plates, and a coiled spring surround-

10

20

ing the cylindrical portion of said crowned member and one end of said spring slidably engaging said pin, whereby when said staff is rotated in one direction said spring will grip said cylindrical portion to prevent rotation of said staff but not grip said portion when the staff is rotated in the opposite direction and said end of said spring engaging said pin regardless of the position to which the staff is slidably moved.
